UNITED STATES PATENT OFFICE.

JESSE G. ZIM, OF MALDEN, MASSACHUSETTS.

GALLEY END LOCK.

1,400,650.

Specification of Letters Patent. Patented Dec. 20, 1921.

Application filed January 28, 1921. Serial No. 440,769.

To all whom it may concern:

Be it known that I, JESSE G. ZIM, a citizen of the United States, residing at Malden, county of Middlesex, Commonwealth of Massachusetts, have invented a certain new and useful Improvement in Galley End Locks, of which the following is a specification, reference being had therein to the accompanying drawings.

10 The object of the invention is to provide an adjustable barrier to prevent the falling down of the lines of type or linotype in the galley and for locking the same in adjusted position. One feature of the invention consists in providing a head member which is normally held with a yielding pressure against the line of type or linotype and which is yieldable to be moved a limited distance to permit corrections to be made by 15 the compositor. Another feature of the invention relates to the adjustable holder for the head member. Another feature relates to the means for locking the holder in its adjusted position.

20 25 For convenience of description, the invention is shown and described as embodied in a device which is commonly called an end lock, but some features of the invention may also be embodied in what is more technically 30 called a composing stick. It is my intention to have the claims broadly construed to cover both a so-called galley end lock and a so-called composing stick wherever the features covered by the claims are applicable to both 35 forms of device.

The invention will be fully understood from the following description when taken in connection with the accompanying drawings, and the novel features thereof will be 40 pointed out and clearly defined in the claims at the close of this specification.

In the drawings, Figure 1 is a plan view of a galley having combined therewith a device embodying the invention, the device being 45 shown in locking position.

Fig. 2 is a side elevation of the device shown in Fig. 1, the locking member being unlocked.

Fig. 3 is an end view as viewed from the 50 left-hand end of Fig. 1.

Fig. 4 is a section on line 4—4 of Fig. 2.

Referring now to the drawings, 1 and 2 represent the two side walls and 3 the head wall of a galley in which is shown a plurality of lines of type or linotype 4. The

end lock comprises an angular member having a side bar 5 which rests against the inside face of the side wall 1 of the galley and a transverse bar or head portion 6, having yieldingly mounted therein a type-stop bar 7.

Means are provided by which the side member 5 may be locked at different positions of adjustment lengthwise of the galley, and the stop bar 7 is yieldingly connected with the transverse head member 6 so that when the head member 6 is rigidly adjusted, the yielding member 7 will normally be held against the type but may be pushed back a limited distance by compressing its spring in order that the compositor may make corrections in the lines of type. In the form of construction shown, the member 7 is provided with pins 8 which are fast thereto and pass loosely through perforations in the head member 6. A spring 9 coiled around each pin 8 intermediate the transverse head member 6 and the stop bar 7 normally causes the bar 7 to be maintained at a spaced distance apart from the member 6. The pins 8 are each formed with a head 10 which forms a stop to limit the spacing apart of the two members 7 and 6.

The side 1 of the galley is formed with a series of perforations 13 which are preferably spaced two picas apart. The side member 5 of the lock is provided with two spring-seated pins 14, each preferably having a cam-surfaced end 15 which engages with one of the holes 13 whenever the pin 14 is brought into alignment with one of said holes. The cam face 25 of the pin allows the lock bar to be easily pushed forward toward the head of the galley even when the pin is engaged with one of the holes, 95 because the cam face will allow the pin easily to ride out of the hole when the locking device is pushed forward with pressure by the hand. The springs 16 cause the pin to snap into one of the holes when the pin comes into alignment therewith.

Preferably the pins 14—14 are five picas apart, while, as already stated, the holes are two picas apart. By this construction the galley lock can be placed within one pica of 105 any desired position. The spring front stop bar 7 of the lock yields also about one and one-half picas so that three entire lines of six-point type can be inserted if necessary when the side bar is locked, and still allow 110

additional movement sufficient for correction.

For convenience of construction and of assembling the spring-seated pins 14 in 5 the side bar of the lock, the said side bar is shown as formed of two members 5 and 18, the member 18 being secured to the member 5 by screws 19. The side bar is formed with holes 17 to receive the pins and the 10 actuating springs. While I have shown the side member as being formed in two parts, 5 and 18, I do not mean to be limited to a two-part construction, nor to the particular form of socket or shape of the pins.

15 Normally the heads of the pins 15 project slightly outside of the outer face of the bar 5 under the pressure of the springs 16, except when they are held back in their sockets by the ends of the pins engaging 20 with the inside face of the side 1 of the galley.

A latch 20 is provided to hold the side bar of the locking device in its adjusted position until the operator desires to release it for readjustment. This latch device 25 comprises a U-shaped member having a top portion 21 and two downwardly extending ears 22-23. The said latch is pivoted at 24 to the inner face of the member 18 of the side 30 bar and is provided with a handle portion 25 for manipulating the latch. When the latch is pressed down the two ears 22-23 will embrace between them the side bar 5 and its clamping member 18 and the side 35 1 of the galley, that is the ear 23 will go down over the outside of the side wall 1 of the galley and the ear 22 will go down over the inside face of the clamping bar 18, as clearly shown in Fig. 3. This will clamp 40 together the side bar of the locking member and the side wall 1 of the galley, so that the side bar cannot be moved laterally to release the pin 15 from the hole in the side wall of the galley. When it is desired to 45 readjust the lock the latch member will be released by lifting the handle 25 into the position shown in Fig. 2, thus allowing the combined side bar and head of the galley lock to be moved slightly laterally away 50 from the side wall 1 of the galley enough to release the pin 15.

While I have described the device as particularly intended for use in connection with a galley end lock, the feature of the spring-seated pins in the side bar is adapted for use in a composing stick, and I therefore intend that so far as relates to that feature the claims shall cover broadly a composing stick as well as what is technically referred 60 to as an end lock.

What I claim is:—

1. A galley end lock having a head which extends transversely of the galley, a type stop bar in front of said head and having 65 loose connection with said head, whereby the

stop bar is capable of a limited movement with relation to said head, springs between the said stop bar and head, whereby the stop bar is normally held spaced away from the said head, and a side bar having spring seated pins projecting laterally therefrom adapted to engage with perforations in the side wall of the galley, and a latch whereby the said side bar may be rigidly locked to the side wall of the galley. 75

2. A galley end lock having a head which extends transversely of the galley, a type stop bar in front of said head and having loose connection with said head, whereby the stop bar is capable of a limited movement 80 with relation to said head, springs between the said stop bar and head, whereby the stop bar is normally held spaced away from the said head, a side bar having spring seated pins projecting laterally therefrom adapted 85 to engage with perforations in the side wall of the galley, and a latch pivoted to the side bar of said galley lock, said latch having downwardly extending ears which when the said latch is closed are adapted to embrace 90 between them the said side bar and the side wall of the galley to rigidly lock the side bar to the galley and prevent lateral movement.

3. A galley end lock comprising a member 95 having a head portion which extends transversely of the galley, and a side portion which extends alongside of the inner face of one wall of the galley, said side member having spring-seated pins mounted in the 100 side-adjacent the galley wall, the springs on which said pins are seated tending to cause the pins to project outside of the said side member, in combination with a galley having a side wall formed with a plurality of 105 apertures with which one of said pins is adapted to engage whenever the side bar is adjusted to bring one of the pins into alignment with one of said apertures.

4. A galley end lock comprising a member 110 having a head portion which extends transversely of the galley, and a side portion which extends alongside of the inner face of one wall of the galley, said side member having spring-seated pins mounted in the side 115 adjacent the galley wall, the springs on which said pins are seated tending to cause the pins to project outside of the said side member, in combination with a galley having the side wall formed with a plurality of 120 apertures with which one of said pins is adapted to engage whenever the side bar is adjusted to bring one of the pins into alignment with one of said apertures, said pins being formed with cam-faced outer ends. 125

5. A device for use in holding type in a galley, having a side member which extends alongside of the inner face of one wall of the galley, said side member having spring-seated pins mounted in the side adjacent the side 130

wall of the galley, the springs on which said pins are seated tending to cause the pins to project outside of the said side member.

6. A device for use in holding type in a galley, having a side member which extends alongside of the inner face of one wall of the galley, said side member having spring-seated pins mounted in the side adjacent the side wall of the galley, the springs on which said pins are seated tending to cause the pins to project outside of the said side member, said pins having cam-surfaced outer ends.

10 7. A device for use in holding type in a galley, having a side member which extends

alongside of the inner face of one wall of the 15 galley, said side member having spring-seated pins mounted in the side adjacent the side wall of the galley, the springs on which said pins are seated tending to cause the pins to project outside of the said side member, in 20 combination with a galley having a side wall formed with a plurality of apertures with which one of said pins is adapted to engage whenever the said side member is positioned to bring one of the pins into alinement with 25 one of said apertures.

In testimony whereof I affix my signature.

JESSE G. ZIM.
